UNITED STATES PATENT OFFICE.

EDWARD FRANKLIN GAMBER, OF SHAMOKIN, PENNSYLVANIA.

WINDOW JACK.

Application filed April 11, 1925. Serial No. 22,448.

To all whom it may concern:

Be it known that I, EDWARD F. GAMBER, a citizen of the United States, residing at Shamokin, in the county of Northumberland and State of Pennsylvania, have invented certain new and useful Improvements in Window Jacks, of which the following is a specification.

This invention is a folding window jack for the use of painters, window washers and mechanics and workmen generally. The main object of the invention is to provide a simple, strong and efficient window scaffold or jack, in a form which may be easily folded up in compact bundle for transportation from place to place.

In the drawing—

Figure 1 is a side elevation showing the device mounted in operative position in a window;

Figure 2 is an end view showing the device mounted in the window;

Figure 3 is a top plan view of the device detached from the window and opened out;

Figure 4 is a bottom plan view of the device;

Figure 5 is an end view of the device folded up.

This invention consists of two planks 1 of suitable length and width for the purpose, and hinged together by means of offset strap hinges 2 mounted along the under sides of the planks, so that when the device is mounted in place in a window, these hinges being on the under side, will help to prevent the planks from buckling together. Furthermore, the hinge joints being offset at right angles from the hinge bodies, as shown at 3, serve, when the device is folded together, to throw the two planks 1 away from each other, so as to leave a sufficient space between them to accommodate the tie rods hereinafter referred to, and so as to make a neat and compact package when folded.

Stay pin plates 4 are secured to the ends 5 of the planks designed for positioning over the sill 6 of the window 7, the said plates and planks being provided with a plurality of laterally aligned or paired stay pin holes 8 adapted to slidably receive stay pins 9 which are thrust through said holes and have a bearing against the inner edge of the window sill 6 in order to anchor the device in place in the window. Brace bearing lugs 10 and 11 provided with tie rod

eyes are screwed also to the under sides of the planks 1 at the outer edges thereof, the lugs 10 at the ends carrying the stay pin holes 8 being spaced sufficiently from those ends to permit the same being projected inwardly through the window with the lugs located adjacent the outer edge of the window sill. The other set of lugs 11 are mounted near the outer ends of the planks. Two legs 12 of bar iron are provided at their ends with eyes 13 corresponding to and adapted to register with the eyes of the lugs 11. Two braces 14 having eyes 15 to register with the eyes of the lugs 10, are provided. Both the legs 12 and the braces 14 are provided with series of aligned or paired tie rod holes 16. Three tie rods 17, 18, and 19 are provided, all identical in form, of a length sufficient to span the width of the planks 1 when opened out, the said rods being threaded at their outer ends and provided with nuts 21. Stop shoulders 22 are formed immediately back of the threaded ends of the tie rod 19. The said shoulders 22 are so located that the distance between their outer faces or edges is approximately equal to the width of the two planks when opened out.

The device is now ready for setting up in the window 7. This is accomplished by opening out the planks 1, and positioning the ends 5 inside the window, the hinges 2 being turned downward. The stay pins 9 are then thrust through the proper set of holes 8. The ends of the rods 17 and 18 are thrust through the eyes of the lugs 10 and 11 respectively and nuts 21 are turned up on the ends thereof. Then the legs 12 are turned inwardly against the wall of the building and the braces 14 are drawn outwardly angularly across the legs 12 and when the planks 1 are properly leveled up the ends of the lower tie rod 19 are inserted through the proper set of holes 16, through the said legs and braces and their nuts 21 are firmly turned up, thus locking the device in operative position. When folded up for transportation, the offset form of hinges employed leaves a sufficient space between the planks for receiving and holding the three tie rods. By mounting two or more of these devices in adjacent windows, scaffold boards may be laid across, thus forming a regular scaffold. These boards may be secured in place in any conventional man-

ner, as by safety pins 23 passed through the outer board and through the planks of the window jacks.

While I have herein described a certain specific manner and method of constructing and assembling the elements of my invention, it is understood that I may vary from the same in minor details, not departing from the spirit of my invention, so as best 10 to construct a practical device for the purpose intended, as defined in the appended claim.

I claim:

15 A device of the kind described, comprising two planks adapted for positioning side by side across a window sill, the planks being provided at their inner ends with a series of laterally aligned stay pin holes; strap hinges connecting the planks at their 20 under adjacent side edges, the joints of the hinges being offset at right angles from the hinge bodies; brace bearing lugs mounted at the outer side edges of the planks, the same being provided with tie rod eyes; a

pair of legs provided medially with a series 25 of laterally aligned tie rod holes and having eyes in their outer ends registering with the eyes of the outer brace lugs; a pair of braces provided medially with a series of laterally aligned tie rod holes and having eyes in 30 their ends registering with the eyes of the inner brace lugs; three tie rods having threaded ends, the ends of the two upper rods being adapted for insertion through the tie rod eyes of the said lugs and the 35 ends of the lower rod through the tie rod holes of the angularly crossed legs and braces for locking the same together, the said lower rod having stop shoulders immediately back of its threaded ends; nuts for 40 the ends of the said rods; stay pin plates mounted on the inner ends of the planks over the said stay pin holes and having holes therethrough registering therewith; and stay pins adapted for insertion through the 45 said stay pin holes.

In testimony whereof I affix my signature.
EDWARD FRANKLIN GAMBER.
